Primary Examiner—Stella Reid**CLAIM**

The ornamental design for a patient leg support, as shown and described.

DESCRIPTION

FIG. 1 is a top, front, right side perspective view of a patient leg support embodying my design;
FIG. 2 is a rear elevational view thereof; and,
FIG. 3 is a left side elevational view thereof, the bottom being plain and unornamental.

FIG. 1

FIG. 2

FIG. 3
